UNITED STATES PATENT OFFICE.

COLONEL GLENN ROWAN, OF KANSAS CITY, MISSOURI.

THERMOSTAT-CONTROLLED ALARM.

Application filed April 60, 1928. Serial No. 274,061.

This invention relates to thermostat controlled fire alarm mechanism whereby an alarm shall be sounded upon the thermostat reaching a predetermined temperature and is primarily intended for use in residences, 5 hotels and factories not equipped with automatic sprinkler systems or other fire protection apparatus.

A further object of the invention is to produce 10 an alarm mechanism which may be used in combination with a remotely located thermostat for effecting operation of the alarm.

A still further object is to produce a 15 strong, durable, efficient and inexpensive construction of the type mentioned; and in order that it may be fully understood, reference is to be had to the accompanying drawings, in which:

Figure 1 is a face view of an apparatus embodying the invention.

Figure 2 is a side elevation of the same.

Figure 3 is an enlarged top plan view with the glass and dial removed and with a part of the frame and base broken away to illustrate parts otherwise hidden.

Figure 4 is a side elevation, partly in section of the construction as shown in Figure 3.

Figure 5 is an enlarged detail of the electrically-operated trip mechanism operated by 30 a remote thermostat.

In the said drawings, where like reference characters identify corresponding parts in all of the figures, 1 indicates a base plate provided with a marginal flange 2 on which a 35 casing 4 is removably mounted. Mounted on the base plate 1 is a spring-motor carrying-frame comprising a top plate 5 and a bottom plate 6 secured together by a series of retaining and spacing bolts and sleeves 8, the upper plate 5 being formed with a pair of 40 transversely extending projecting ribs 9 acting as supports for a dial plate 10 provided with suitable temperature indicating marks 11. In abutment with a face of the dial 10 is a spacing collar or ring 12 against which a glass plate 13 is held for means of a flange 14 on the casing 4. The base plate 1 on its side opposite from the spring-motor frame is integrally formed with a tubular internally 45 threaded extension 15 providing a support for a gong 16, said gong having a stem (not shown) threaded into said extension. The gong is preferably of substantially the diameter of casing 4 so that it shall provide a housing 55 for mechanism hereinafter described.

Mounted between the upper plate 5 and the

base plate 1 is a spring motor 17 having a squared winding shaft 18 projecting through plate 1. Carried by the shaft 18 and in close proximity to the plate 5 is a drive gear 19 enmeshed with a pinion 20, said pinion being keyed on a shaft 21 journaled at one end in the plate 5 and at its other end projecting through and journaled in the base 1. The shaft 21 at its outer end carries a star-wheel 22 co-operating with a dog 23 oscillatably mounted on a fixed shaft 24 carried by the base 1, said dog being integrally formed with a clapper 25 for operation of the gong. The clapper 25 is operated in one direction by the dog 23 and star-wheel 22 and in the other direction by a retractile spring 26 secured to a pin 27 carried by the base 1. The shaft 18 on the outer face of the base plate 1 carries a detent wheel 28 which is prevented from 75 rotation in one direction by a spring dog 29 held in engagement with the wheel by a spring 30, so that the motor cannot unwind during a winding operation as will be readily understood. Enmeshed with the gear wheel 19 is 80 a pinion 31 on a shaft 22 having its opposite ends journaled in the plates 5 and 6, and said shaft carries a large gear 33 enmeshed with a pinion 34 on a shaft 35 journaled at its opposite ends in said plates. The shaft 35 also 85 carries a gear wheel 36 enmeshed with a pinion 37 on an escapement shaft 38 journaled between the plates 5 and 6. The shaft 38 carries an escapement wheel 39 controlled by pallets 40 on an oscillating stop lever 41 90 integrally formed with a shaft 42 journaled between plates 5 and 6.

From the above description and referring to Figure 3, it will be evident that with the pallets in locked position as illustrated, the 95 spring motor 17 is held against operation, but that upon release of the lock lever 41 the escapement wheel 39 will be freed for operation and the train of gearing will rotate, the drive gear 19 effecting operation of the gong 100 operating shaft 21. To provide thermostat control mechanism to trip the locking or stop lever 41, a shaft 42^a is journaled at its lower end in the plate 6 and projects through the upper plate 5 and the dial 10, and at its upper 105 end carries an indicating finger 43 for registering with the dial marks 11. The end of the shaft 42^a is squared as at 44 and secured to said squared portion is one end of a spring thermostat 45, the opposite end of said spring 110 thermostat being secured to an anchor 46 carried by the plate 6. Mounted on the shaft

42 above the thermostat spring is a cam 47 having a notch 48.

Journaled between the plates 5 and 6 is a shaft 49 formed integrally with a catch lever 50 normally having one end in abutment with the end of the lock lever 41 as illustrated, and having its opposite end in contact with the cam 47, said lever being held pressed against the cam by a retractile spring 51 secured at 10 its opposite end to a post 52. The cam 47 is so arranged on the shaft 42 that when the temperature reaches a predetermined degree, the cam will rotate until the end of the lever 50 drops into the notch 48. This movement 15 of lever 50 frees the locking lever 41 so that the escapement wheel may rotate to set the gong in operation as above described. The gong will consequently be sounded at predetermined intervals as controlled by the period 20 of the oscillation of the pallet-equipped locking lever 41.

In order to stop the operation of the device and at the same time reset the trip mechanism a shaft 53 is journaled at its opposite 25 ends in plates 5 and 6, and at one end said shaft projects through the base plate 1 and at its extremity is fitted with an operating knob 54. The shaft 53 carries a cam 55 in the same plane as the levers 41 and 50, said cam being 30 normally held in inoperative position against a stop pin 56 as shown in Figure 3, by a spring 57 coiled on said shaft. When the shaft 53 is rotated in the direction of the arrow, the cam 55 first strikes the lever 41 and moves it in the direction of the arrow appended thereto, and continued movement of the cam while 35 maintaining the lever 41 in repressed position finally effects oscillation of the lever 50 and moves it in the direction of the arrow appended thereto. This action moves the end of 40 the lever 50 out of the notch 48 in the cam 47, and said cam immediately returns to normal position under the action of the thermostat spring 45. The other end of the lever 50 is 45 moved to position shown in Figure 3 for the locking of the escapement lever 41. Upon release of the knob 54, the cam 55 is returned to normal position by its spring 57, and the device is ready for further operation.

50 Under some circumstances it may be desirable to provide thermostatically controlled switches at points remote from the gong so that should an undue temperature develop at any of such points, the gong will be operated. In order to effect operation of the 55 gong, it will be obvious that the cam 47 must be rotated until the end of lever 50 drops into the notch 48, and one means of accomplishing this result is illustrated in Figure 5, a fragmental view indicating the cam 47, the ther-

mostat 45 and end of lever 50. Integrally formed with the upper face of the cam 47 and projecting therefrom, is a lever arm 58 carrying an electrical-magnet pole-piece 59 for attraction by an electrical-magnet 60. Upon 65 the closing of an electrical circuit through the magnet, it will be evident that it will attract the pole-piece 59 and effect rotation of the thermostat shaft to trip the alarm mechanism in the same manner as if tripped by expansion of the thermostat. When the circuit is broken, the device may be reset as above described and will be ready for further operation.

70 From the above description it will be apparent that I have produced a device possessing all the features of advantage set forth as desirable and, while I have described and claimed the preferred embodiment of the same, it is to be understood that I reserve the right to make all changes properly falling 75 within the spirit and scope of the appended claims.

I claim:

1. The combination of a spring motor, of 80 a gong operated by said motor, escapement mechanism to control operation of the motor, means to prevent operation of said escapement, a cam for effecting release of said last-named means, and a thermostat for actuating 85 said cam.

2. The combination of a spring motor, of a gong operated by said motor, means to lock the motor against operation, means to trip 90 said locking means, and thermostatic means 95 to release the last-named means.

3. The combination with a spring motor, of a gong operated by said motor, an escapement to prevent operation of the motor, a cam to prevent operation of the escapement, 100 and a thermostat to effect operation of the cam.

4. The combination with a spring motor, of a gong operated by said motor, an escapement to prevent operation of the motor, a lever normally holding the escapement against operation, a cam normally retaining the lever in locked position, and a thermostat for effecting operation of said cam.

5. The combination with a spring motor, of a gong operated by said motor, means to lock the motor against operation, means to trip said locking means, thermostatic means to release the last-named means, and manually-operable means to move the locking 110 and tripping means to permit the thermostat operated means to return to normal position.

115 In testimony whereof I affix my signature.

COLONEL GLENN ROWAN.
